UNITED STATES PATENT OFFICE.

WILLIAM E. CURRIE, OF DETROIT, MICHIGAN.

DUMPING-WAGON.

No. 836,670.

Specification of Letters Patent.

Patented Nov. 27, 1906.

Application filed October 30, 1905. Serial No. 285,048.

To all whom it may concern:

Be it known that I, WILLIAM E. CURRIE, a citizen of the United States of America, residing at Detroit, in the county of Wayne and State of Michigan, have invented certain new and useful Improvements in Dumping-Wagons, of which the following is a specification, reference being had therein to the accompanying drawings.

10 The invention relates to dumping-wagons, and more particularly to that type in which the tilting of the bottom section of the wagon to discharge the load lifts the sides of the wagon-box and after the load is discharged 15 the weight of said box operates to return the tilted bottom to normal position.

15 The invention consists in certain novel features of construction, as hereinafter set forth.

20 In the drawings, Figure 1 is a central longitudinal section, and Fig. 2 is a top plan view.

25 Heretofore dumping-wagons have been constructed in which the box of the wagon-body is hinged at its rear end to the frame, the bottom board of said body being pivotally secured to the frame, so as to be capable of tilting and in so doing raising the forward end of the box. The length of the wagon-body is limited to that which will permit the 30 bottom section to tilt to the required angle for discharging its load, and greater length cannot be obtained without correspondingly raising the height of the frame above the ground. Thus to secure the necessary capacity for the wagon-box the sides thereof must be considerably increased in height over ordinary constructions. With the present invention I have increased the length of 35 the wagon-box by extending the frame rearward beyond the rear axle, limiting the length of the tilting bottom section which raises the box so as to clear said axle and providing an auxiliary tilting bottom section for the portion of the box in rear of the axle. 40 I have further provided connections by which the movement of the rear section of the bottom is automatically effected by the tilting of the forward section.

45 A is a forward truck, B the rear axle, and C a frame connecting the same and which projects rearwardly beyond the rear axle.

50 D is the wagon-box, comprising sides and ends, which is connected to the frame C at its rear end by a hinged connection E.

55 F is a bottom section which extends be-

neath the forward portion of the body, terminating just in front of the rear axle, said section being pivotally secured to the frame at G at a point forward of its center, so that 60 the load supported on the section will be out of balance. The forward end of the section F has a bearing on the lower edge of the forward portion of the wagon-box, and thus when the section is tilted said box will be 65 raised.

In rear of the axle B is a bottom section H, which is also pivoted, but preferably to the box D instead of the frame, as at a. The location of this pivot is such in relation to the rear axle that when the body D is lowered into its normal position a portion of the section H will rest upon the axle B and will be supported thereby in contact with the box. As soon, however, as the box D is raised the 70 shifting of position of the pivot a relative to the axle will permit the section H to assume the inclined position necessary to discharge its load. Upon the dropping of the wagon-box the section H will be again tilted upward 75 by contacting with the axle B during the lowering of the pivot a.

In order to prevent the material constituting the load in the wagon from lodging in the axle and going beneath the portion of the 80 section H resting on said axle, I preferably provide a guard over the adjacent edges of the sections F and H. This guard I, as shown, also constitutes a division of the wagon-box, being inclined forward from its 85 base to the top, so as to produce a hopper-shaped receptacle above the bottom section H. A second guard J is preferably secured to the rear axle B and arranged to project 90 upward between the separated walls b and c 95 of the guard or division I. This second guard is for the purpose of preventing any of the load in the forward portion of the wagon-box from discharging on the axle after the box is raised and the guard I carried thereby 100 above the axle.

To support the load, locking-latches are provided for the tilting sections F and H, which are shown in the form of dogs K and L, connected for simultaneous operation by the rod M and actuated by suitable connections. (Not shown.) Thus to discharge the load it is merely necessary to disengage the dogs K and L, which will permit the weight 105 of the load on the rear section of the bottom section F to tilt said sections, lifting the box D, and thereby tilting the rear section H.

As soon as the load is discharged the weight of the box will return the sections, which may be locked by the dogs K and L, restoring the wagon in a condition for receiving 5 another load.

What I claim as my invention is—

1. In a dumping-wagon, the combination with forward and rear axles, of a bottom formed of two tilting sections and a wagon-10 box resting on said sections, one of said sections extending beneath the forward portion of the box and terminating adjacent to the rear axle and the other extending over the rear axle to the rear end of said box.
- 15 2. In a dumping-wagon, the combination with forward and rear axles, of a frame supported thereon and extending rearward beyond the rear axle, a wagon-box hinged to said frame at its rear end, a tilting bottom 20 section pivotally secured to said frame and extending over the forward end of the body to the rear axle, said section being adapted in tilting to raise the forward end of the body, and a second section pivotally connect-25 ed to said box and extending over the rear axle to the rear end of the box.
3. In a dumping-wagon, the combination with a box, of tilting bottom sections for said

box and a division for said box forming a guard covering the adjacent ends of said tilting sections. 30

4. In a dumping-wagon, the combination with a frame and vertically-movable box-walls thereon, of a bottom for said box formed of a plurality of tilting sections, one of said sections being pivoted to said frame and adapted to raise the box in tilting and another section being connected to the box and tilted by the rising thereof. 35

5. In a dumping-wagon, the combination with a frame and vertically-movable box-walls thereon, a bottom for said box formed of two tilting sections, one of said sections extending from the forward end of the box to the rear axle and another section extending 40 from the rear axle to the rear end of the box, the forward section being pivoted to said frame and the rear section being pivoted to the box and normally resting on the top of the rear axle. 45

In testimony whereof I affix my signature in presence of two witnesses.

WILLIAM E. CURRIE.
